HEEL-LIFT-ASSEMBLING MACHINE.

1,223,728.

Specification of Letters Patent.

Patented Apr. 24, 1917.

Application filed May 4, 1912, Serial No. 695,018.

Renewed September 22, 1916. Serial No. 121,687.

To all whom it may concern:

Be it known that I, ERVIN L. PAGE, a citizen of the United States, residing at Georgetown, in the county of Essex and State of Massachusetts, have invented an Improvement in Heel-Lift-Assembling Machines, of which the following is a specification.

In the manufacture of pasted heels it has been customary to drive a nail through the middle portion of the heel at the time the heel is built, and then, later to place the heel in a press, to press the lifts together. As the driving of the nail through the middle portion does not cause the application of pressure about the edge portions of the heel, but, on the contrary, rather tends to cause the joint between the lifts to open, if the pressure is not immediately applied about the edge portion of the lifts, the cement dries so that when the pressure is finally applied the edge portions are likely not to adhere, so that the heel will check. To avoid this difficulty it has been customary to apply a surplus amount of cement to the lifts, but this method is ineffective to a large extent.

The use of the nails for securing the lifts together is objectionable, not only on account of the expense of the nails, but they are sometimes driven in places where they interfere with the heel-attaching operation.

If the heel is compressed over its entire surface immediately after the paste has been applied and held under pressure for a sufficient time to permit the paste to set, the lifts will be firmly cemented together, so that they will not check and the use of the connecting-nails and of surplus paste may be avoided.

The object of my invention is to provide a heel-assembling machine in which the lifts may be assembled in an ordinary heel building form, and may, immediately thereafter, and without removing them from the form, be placed under pressure over their entire area, and be thus held until the lifts have been caused to adhere firmly throughout their entire areas, so that they will not thereafter check, and the use of the connecting-nails will be made unnecessary.

A further object is to provide a heel-lift

assembling machine in which the assembling operation may be carried on more rapidly, so far as I am aware, than with the methods now in general use.

I accomplish these objects by the means shown in the accompanying drawing, in which,

Fig. 1 is a side elevation of a lift-assembling machine made according to my invention.

Fig. 2 is a cross section on line $x-x$, of Fig. 1.

Figs. 3, 4 and 5 are enlarged sectional views of a heel-lift-receiving form, which I employ, showing the parts in different positions.

Fig. 6 is a plan view thereof.

Figs. 7 and 8 are detail plan views of different parts of the form.

Fig. 9 is a detail sectional view of one of the engaging lugs between a form and the driving wheel.

The frame of the machine preferably comprises two parallel, vertically disposed, and horizontally extending sections 1, 2, of materially greater length than height and supported on legs, in the manner indicated in Fig. 1. A pair of shafts 3 and 4 are journaled in said frame at opposite ends thereof, and a pair of octagonal-shaped disks 5 and 6 are centrally secured on said shafts 3 and 4, respectively, forming wheels, the edges of said disks providing a series of heel-form supporting faces 5' and 6', as hereinafter described. A series of cross bars 7, forming rigid abutments, are fixed between the disks 5, one being arranged between the middle of each face 5' and the corresponding center of the disks.

A series of heel-form bases 8 are connected by links 9 in the form of an endless chain, or carrier, which is arranged to be carried about the disks 5 and 6 as they are rotated, so that each base will be successively supported on the faces 5' and 6', as the disks are rotated.

In order that the same relative position may be maintained between the chain and the disks, any suitable engaging means may be provided therebetween, which will prevent relative slipping, as for example, lugs

10 on the disks 5, which are arranged to engage corresponding recesses, in a manner corresponding to the ordinary sprocket and chain.

5 The base 8 has a recess 8' formed in the upper side thereof, which extends about a lift-shaped middle portion 11, which constitutes the bottom of the heel form. A removable form section is provided for each 15 size of heel, and comprises a supporting-plate 12 which is adapted to fit in said recess 8', said plate 12 having a central aperture into which said base portion 11 fits and extends, so that it is flush with the surface thereof, and screw buttons 13 being provided in base 8 to secure the plate 12 in place thereon. Two pairs of lift-holding plates 14 are vertically mounted on the plate 12, said plates 14 being bolted to the 20 sides of vertical lugs 15 mounted on the plate 12, and the upper ends of said lugs are connected by guard plates 16. Said plates 14 are divergently arranged with relation to the base portion 11 and have 25 notched inner edges outwardly inclined so that they correspond to the shape of the heel which is to be built on the base portion 11. A breast-gage 17 is also mounted on the plate 12 in the necessary relation to the 30 plates 14, so that a lift-receiving recess is provided which will move the lifts into the desired relation when they are piled therein.

A U-shaped operating device is provided which comprises a cross-bar 18 arranged beneath the base 8, said device being preferably formed of a stiff wire, or rod bent to form a horizontal middle portion and two end portions, which are slightly inclined downwardly, and are then extended upwardly to form a pair of guide rods 19, which are reciprocally mounted in apertures in the base 8, at each side of the plate 12. Bosses 20 are provided about the aperture through which said members pass to increase the guiding surface therefor. An end section, or arm 21 is pivotally connected to the end of each guide rod 19, the diameter thereof being the same as the diameter of said rods and the joint therebetween being 45 adapted to slide freely in the apertures through the base 8, the end portions of the sections 21 passing through the ends of a cross-bar 22, which is adjustably connected thereto by means of thumb nuts. Said bar 50 22 is provided with a lift-shaped clamping plate 23 at its middle portion, arranged in position to be drawn down onto a heel in the form as hereafter explained.

A plunger 24 is reciprocally mounted in 60 an aperture through the middle of the base portion 11 and is notched at its lower end and arranged astride the cross-bar 18, and a spring 25 is arranged on said plunger between the base 8 and the bar 18, so that said

spring tends to draw the guide rods 19 and 65 therefore the plate 23 downwardly.

A deflector 26 is mounted on the frame beneath the wheel 5 and is provided with an engaging face which extends from a point midway between the wheel disks 5, and a 70 short distance below the lowermost faces thereof, upwardly and rearwardly therefrom.

A ratchet 27 of any suitable form is secured on the shaft 3 and an arm 28 is 75 mounted to swing on the shaft 3, and carries a pawl 29 in position to engage the ratchet 27. A link 30 is connected at its lower end to a treadle 31 and at its upper end to the end portion of the arm 28, and a lifting 80 spring 32 is connected to said treadle and the frame. The ratchet 27 is provided with the same number of teeth as the disks 5 have faces 5', so that each time the treadle is depressed the shaft 3 will be rotated, (in 85 the present instance) one eighth of a turn.

The manner in which the machine is operated is as follows:—

When the parts are in the position of Fig. 1, the cross-bar of the heel-form which is 90 resting on the disk 5, and, is in the uppermost position thereof, so that it is supported horizontally, will be supported by the corresponding cross-rod 7, so that the guide- 95 rods will be held in such a position that the joint between said rods and the links will be above the ends of the bosses, and said end-sections 21 will be swung down to a nearly horizontal position, so that the clamping plate will be held at one side of 100 the form and in such a position that the lifts may be conveniently placed in the form by hand in the usual manner. The lifts are pasted and placed therein, in regular order according to sizes, the smallest first. The 105 treadle is then depressed, moving the shaft 3 and parts carried thereby one eighth of a revolution. This movement will cause the disks 5 to drive the form carrier a distance 110 equal to the distance between two forms.

As the carrier is driven, the form which was supported on the upper faces of the disks 5 will be moved horizontally, toward the wheel 6, while the bar 7, which engaged its cross-bar 18, will be moved downwardly 115 about the center of the shaft 3, so that said parts will move divergently; and, by the time the movement from one position to the next is finished, the bar 7 will have been moved entirely out of engagement with the 12 bar 18. This movement permits the spring 25 to depress the cross-bar 18, and depression of the latter causes the rods 19 to be drawn downwardly. As soon as the under side of the end sections 21 engage the rear side of the bosses 20 they will be thrown upwardly, and, by the time the joints between the rods 19 and said sections have been 13

drawn into the bosses 20 said sections will have been moved to an upright position, so that the plate 23 will be held directly over the heel-lifts which have just been piled into the form.

As the spring 25 continues to draw the rods 19 downwardly, the plate 23 will be drawn down until it is seated on the uppermost lift which has been piled in the form, causing the lifts to be moved into position, if they were previously disarranged and also pressing the lifts together, onto the base portion 11 under the tension of spring 25. The tension of the spring 25, when it has been permitted to expand to the point where the plate 23 presses the lifts together, is made sufficient to press them with sufficient force to cause the entire surfaces thereof to be pressed in close contact, and, as the plate 23 bears on substantially the entire surface of the upper and largest lift, the joint at the edges of the lifts will be pressed closely together. It follows, therefore, that when the form, which has just been filled, is moved to the next position beyond the point at which it was filled, the lifts therein will be placed under a firm pressure and will be thus held by the spring 25.

In Fig. 1, the clamping-plate 23 of the form which has been filled, and has been moved to one position beyond the filling position, is shown in an intermediate position, for the purpose of illustration, but, in practice is moved to the clamping position shown by the next adjacent form, practically as soon as the bar 7 moves out of engagement with its cross-bar 18. This operation is continued as above described, each form being filled and moved from one position to the next by successive operations.

When a form containing a heel has passed about the disks or wheel 6, and, as it is moved in inverted position to a position directly beneath the lowermost faces 5' of the disks 5, that is, into a position diametrically opposite the filling position, the corresponding bar 7 will engage its cross-bar 18, and will press the bar 18 downwardly, or radially outward from the center of the shaft 2, so that the clamping-plate 23 will be moved out of pressing engagement with the heel, as shown in Figs. 1, 2 and 5. At the same time the plunger 24 will be forced outwardly, and as the length thereof is adjusted so that it will extend slightly beyond the surface of the bottom portion 11 of the base 8, when the bar 18 is moved outwardly to the fullest extent, it will engage the heel and dislodge it from the form, in case the heel should have become adhered to any portion thereof, and the heel will then rest upon the plate 23, as shown in Figs. 1 and 2. The time which it has taken for the form to travel from the position in which the heel

was clamped to the position in which it is unclamped is sufficient to permit the paste between the lifts to have become thoroughly set and the lifts to have adhered firmly to each other, so that, when the heel is discharged from the form, the lifts will not fall apart.

When the form is moved from the lowermost, or unclamped position to the next position upon the succeeding operation, the deflector 26 will engage the adjacent end section 21 and swing the same, together with the other section 21 and the cross-bar 22, to one side, so that the clamping-plate 23 will be moved from the full line position of Fig. 5 to the dotted line position in the same figure, and the heel will be discharged into a receptacle 34, which may be arranged directly therebeneath. The plate 23 will be held in this position until the form is carried to the filling position already described, and then the operation above described will be repeated.

The operation may thus be carried on indefinitely, the forms being successively filled, and, the lifts being automatically clamped, unclamped and discharged without in any way interfering with the building operation.

The lifts of the heel thus produced will be firmly pasted together, and the necessity of using a securing nail for the lifts will be avoided. Moreover, a large saving of time will be secured, on account of the fact that it is not necessary to remove the heel from the form by hand after the lifts have been placed therein, and the operation of depressing the treadle to move the forms out of filling position may be performed without appreciable delay.

When it is desired to build heels of different sizes or shape from those which the machine is fitted to receive, the plates 12 are removed and similar plates having differently formed lift-receiving recesses are substituted in place thereof, all said plates being interchangeable. This change may thus be quickly made without difficulty and it is only necessary to have one set of forms for each shape of heel.

I claim:

1. In a heel-lift assembling machine, supporting-means, an endless flexible carrier extending about said supporting-means and comprising a series of heel-lift forms opening outwardly, means to move said carrier about said supporting-means, a clamping-device for each form, and means to move each clamping-device to compress the lifts while in its form.

2. In a heel-lift assembling machine, a support, a series of heel-holders, flexibly connected to form an endless carrier, and each having a lift-receiving seat, means to drive said carrier to bring each holder suc-

- cessively to a lift-receiving position in which its seat faces upwardly, forming means to guide the lifts into heel form when assembled on the seat of each holder while in said receiving position, a clamping device for each holder and means to move each clamping device to clamp the lifts on the seat of its corresponding holder while held in position by said forming means.
3. In a heel-lift assembling machine, a series of heel forms flexibly connected to form an endless carrier, means to drive said carrier, and a support for said carrier arranged to conduct the same in a semi-circular path about a horizontally disposed axis, said forms being arranged to open outwardly with relation to said axis, and each having a clamping device and means to move the same inwardly, with relation to said axis, to press the lifts against the bottom of its form.
4. In a heel-lift assembling machine, a series of heel forms flexibly connected to form an endless carrier, means to drive said carrier, and a support for said carrier arranged to conduct the same in oppositely disposed, semi-circular paths, about separated, horizontally disposed axes, and horizontally therebetween, said forms being arranged to open outwardly with relation to said axes and each having a clamping device and means to move the same inwardly with relation to said axes to press the lifts against the bottom of its form.
5. In a heel-lift assembling machine, a series of heel forms flexibly connected to form an endless carrier, means to drive said carrier, and a support for said carrier arranged to conduct the same in oppositely disposed, semi-circular paths, of approximately equal radii, and about parallel, horizontally disposed axes, separated to provide elongated horizontal path-portions therebetween, said forms being arranged to open outwardly with relation to said axes and each having a clamping device and means to move the same inwardly with relation to said axes to press the lifts against the bottom of its form.
6. In a heel-lift assembling machine, a series of heel forms flexibly connected to form an endless carrier, means to drive said carrier, and a support for said carrier arranged to conduct the same in an oblong path having curved end portions and horizontal middle portions said forms being arranged to open radially outward with relation to the curved portions of said path and each having a clamping device and means to move the same inwardly to press the lifts against the bottom of its form.
7. In a heel-lift assembling machine, a series of connected heel-lift forms successively movable from a lift-receiving position, a clamping-device for each form, and means to move each clamping-device into position to press the lifts together as its corresponding form is moved from receiving position.
8. In a heel-lift assembling machine, a series of lift-receiving forms connected to form an endless carrier and movable to conduct the forms successively to and from lift-receiving position, a clamping-device for each form, means to hold each clamping device in an inoperative position at one side of its form when in lift-receiving position, and means to move said devices to clamp the lifts against the bottom of the corresponding forms as they are moved from lift-receiving position.
9. In a heel-lift assembling machine, a series of connected heel-lift forms successively movable from a lift-receiving position to a heel-discharging position, a clamping-device for each form, each clamping-device being movable to press the lifts together in its form when moved from lift-receiving position, and means to move the clamping device to permit the heel to be discharged as the form is moved into discharging position.
10. In a heel-lift assembling machine, a series of connected heel-lift forms successively movable from a lift-receiving position to a heel-discharging position, a clamping-device for each form, each clamping-device being movable to press the lifts together in its form when moved from lift-receiving position, and means automatically movable to discharge the heel from the form, as the form is moved into discharging position.
11. In a heel-lift assembling machine, a series of connected heel-lift forms successively movable from a lift-receiving position to a heel-discharging position, a clamping-device for each form, each clamping-device being movable to press the lifts together in its form when moved from lift-receiving position, and automatic means to move the clamping-device out of clamping position as the form is moved into discharging position.
12. In a heel-lift assembling machine, a series of connected heel-lift forms successively movable from a lift-receiving position to a heel-discharging position, a clamping-device for each form, and automatic means to move each clamping-device and press the lifts together in its form when moved from lift-receiving position and to move it to permit the discharge of the heel from the form as the form is moved into discharging position.
13. In a heel-lift assembling machine, supporting-means, an endless flexible carrier extending about said supporting-means and comprising a series of heel-lift forms opening outwardly, means to move said carrier

about said supporting-means, a clamping-device for each form, and means to operate each clamping-device automatically during the movement of the carrier.

- 5 14. In a heel-lift assembling machine, supporting-means, an endless flexible carrier extending about said supporting-means and comprising a series of heel-lift forms opening outwardly, means to move said carrier about said supporting-means, a clamping-device for each form, and means to operate each clamping-device successively to clamp the lifts in its corresponding form, as the form is moved past a predetermined point.
- 10 15. In a heel-lift assembling machine, supporting-means, an endless flexible carrier extending about said supporting-means and comprising a series of heel-lift forms opening outwardly, means to move said carrier about said supporting-means, a clamping-device for each form, and means, automatically operated as the carrier is driven, to move said clamping-devices successively to positions to press the lifts together in the corresponding forms.
- 15 16. In a heel-lift assembling machine, supporting-means, an endless flexible carrier extending about said supporting-means and comprising a series of heel-lift forms opening outwardly, means to move said carrier about said supporting-means, a clamping-device for each form, each movable between a discharging and a clamping position, and means to move said clamping-devices successively from discharging to clamping position as the carrier is moved.

- 20 17. In a heel-lift assembling machine, supporting-means, an endless flexible carrier extending about said supporting-means and comprising a series of heel-lift forms opening outwardly, a clamping-device for each form, each movable between a discharging and a clamping position, driving means to move the carrier in one direction, about said supporting-means, means to hold said clamping-devices in clamping position, and means, actuated by said driving means, as it is operated, to move each clamping-device to discharging position at a predetermined point in the travel of the carrier.
- 25 18. In a heel-lift assembling machine, supporting-means, an endless flexible carrier extending about said supporting-means and comprising a series of heel-lift forms opening outwardly, a clamping-device for each form, movable between discharging and clamping positions, driving means to move the carrier in one direction, about said supporting-means to move said forms successively from and to a filling position, means, actuated by said driving means, to move each clamping-device to clamping position as the corresponding form is moved from filling position, and means to move each clamping-device to discharging position as

the corresponding form is being returned to said filling position.

19. In a heel-lift assembling machine, supporting-means, an endless flexible carrier, extending about said supporting-means and comprising a series of heel-lift forms opening outwardly, and driving means to move said carrier intermittent about said supporting-means to a series of predetermined positions, and a clamping-device for each form movable to compress the lifts therein and to permit their discharge. 75

20. In a heel-lift assembling machine, an endless carrier comprising a series of flexibly connected heel forms opening to the outer side of the carrier, means to support said carrier at its inner side to move horizontally and vertically about horizontal axes, and a clamping-device for each form, movable to compress the lifts therein, and 85 permit their discharge.

21. In a heel-lift assembling machine, an endless carrier comprising a series of flexibly connected bases having heel forms on the outer sides thereof, a clamping-device, 90 mounted on each base movable to clamp the lifts in the form thereof, and means to move the carrier in one direction to bring the forms successively into a horizontal position. 95

22. In a heel-lift assembling machine, an endless carrier comprising a series of outwardly opening and flexibly connected heel forms, a lift clamping-device for each form, vertically movable therein, means to move the carrier in one direction successively to bring the forms into filling and discharging positions, and means to move each clamping-device to compress the lifts as the corresponding form is moved from filling position and to move it to release the lifts as the form is moved toward discharging position. 105

23. In a heel-lift assembling machine, an endless carrier comprising a series of flexibly connected bases each having a lift-receiving recess therein, a clamping-device movable in said recess to clamp the lifts against the bottom thereof, means to drive said carrier in one direction successively to conduct the forms from and to a filling position, engaging devices disposed to move said clamping-devices away from the base at a predetermined point in the travel of the carrier, and means to move said clamping-devices to clamp the lifts as the corresponding forms are moved from filling position. 115

24. In a heel-lift assembling machine, a heel-form having a lift-receiving recess, and movable to and from a lift-receiving position, a clamping plate mounted thereon and movable vertically and laterally relative to said recess to clamp the lifts therein and to permit their removal, means to move 125 130

said clamping plate out of clamping engagement with the lifts as said form is moved toward said position, and means thereafter to effect lateral movement of said plate to permit the heel to be discharged from the form.

25. In a heel-lift assembling machine, supporting means, an endless carrier comprising a series of flexibly connected heel-forms arranged to be driven in an upright plane, about said supporting means, a heel-lift clamping device for each form, means to effect movement of said clamping device into clamping engagement with the lifts when the form is in a position to open upwardly, and means to move said clamping device out of clamping engagement with the lifts when the form is in a position to open downwardly.

26. In a heel-lift assembling machine, a heel-form having a lift-receiving recess, means to move said form to and from a lift-receiving position, a lift clamping plate supported by said form adjacent said recess and movable from a position at one side of said recess to a position thereover, means to move said plate to clamp the lifts against the bottom of said recess, as the form is moved from said position, and means to move said plate to release the lifts, and to permit the plate to be moved to one side of said recess, as the form is moved toward said position.

27. In a heel-lift assembling machine, a heel form comprising a base having a lift-receiving recess, a pair of rods mounted to slide vertically at opposite sides of said recess and having a cross-rod connecting their lower ends beneath the base, a spring interposed between the base and said cross rod to draw the rods downwardly, an arm pivoted to the upper end of each rod, a cross bar connecting the free ends of said arms, a lift-clamping plate on the middle portion of said bar and arranged to be held over said recess when said rods and their respective arms are in alinement and to be moved to one side thereof as said arms are swung downwardly, and abutments on said base arranged to engage said arms adjacent their pivots to swing said arms upwardly into alinement when said rods are drawn downwardly.

28. In a heel-lift assembling machine, an endless carrier comprising a series of flexibly connected heel forms, supports about which said carrier is moved, and means to drive said carrier intermittently to bring said forms successively into a predetermined position, and a clamping plate for each form movable to clamp the lifts therein as the form is moved from said position.

29. In a heel-lift assembling machine, a rotatably mounted wheel, a support at one side of said wheel, an endless carrier extending about said wheel and said support and

comprising a series of flexibly connected heel forms opening outwardly with relation to the axis of the wheel, a lift clamping plate for each form outwardly and inwardly movable therein, means for driving said wheel and said carrier, a series of abutments on said wheel, and operating devices connected to said plates disposed to be engaged by said abutments as their corresponding forms pass into engagement with the wheel to move said plates outwardly at predetermined points.

30. In a heel-lift assembling machine, supports, an endless carrier extending about supports comprising a series of flexibly connected heel forms opening outwardly, a lift-clamping plate for each form outwardly and inwardly movable therein, means to drive said carrier, means to permit lateral movement of said plates when in an outer position, engaging means independent of said carrier, operating devices connected to said plates and disposed to be engaged by said engaging means as said carrier is driven to move said plates outwardly, and means to effect lateral movement of said plates while held in an outer position.

31. In a heel-lift assembling machine, a rotatably mounted wheel, a support at one side of said wheel, an endless carrier extending about said wheel and said support and comprising a series of flexibly connected heel forms opening outwardly with relation to the axis of the wheel, a lift-clamping plate for each form outwardly and inwardly movable therein, means to drive said wheel and said carrier, a series of abutments on said wheel, operating devices connected to said plates disposed to be engaged by said abutments as their corresponding forms pass into engagement with the wheel, to move said plates outwardly at predetermined points, and springs for moving said plates inwardly to clamp the lifts in the forms as said operating-devices are moved out of engagement with said abutments.

32. In a heel-lift assembling machine, a rotatably mounted wheel, a support at one side of said wheel, an endless carrier extending about said wheel and said support and comprising a series of flexibly connected heel forms opening outwardly with relation to the axis of the wheel, a lift clamping plate for each form outwardly and inwardly movable therein, means to drive said wheel and said carrier, and means to move said plates inwardly to clamp the lifts in the forms as the forms successively move out of engagement with the wheel.

33. In a heel-lift assembling machine, a rotatably mounted wheel, a support at one side of said wheel, an endless carrier extending about said wheel and said support and comprising a series of flexibly connected heel forms opening outwardly with relation

to the axis of the wheel, a lift-clamping plate for each form outwardly and inwardly movable therein, means for driving said wheel and said carrier, means to move said plates inwardly to clamp the lifts in the forms, as the forms are successively moved out of engagement with the wheel, and means to move said plates outwardly to release the lifts as the forms are moved into engagement therewith.

34. In a heel-lift assembling machine, a rotatably mounted wheel, a support at one side of said wheel, an endless carrier extending about said wheel and said support and comprising a series of flexibly connected heel forms opening outwardly with relation to the axis of the wheel, a lift-clamping plate for each form outwardly and inwardly movable therein, means for driving said wheel and said carrier, means to move said plates inwardly to clamp the lifts in the forms, as the forms are successively moved out of engagement with the wheel, means to move said plates outwardly to release the lifts as the forms are moved into engagement therewith, and means to move the plates laterally to permit the discharge of the heel as the forms are moved about the wheel.

35. In a heel-lift assembling machine, a rotatably mounted wheel having a regular series of peripheral faces, a support at one side of said wheel, an endless carrier extending about said wheel and said support and comprising a series of flexibly connected heel form bases having lift-receiving recesses opening outwardly, said bases being adapted to be successively held on said faces as the carrier is driven, means to drive said wheel and said carrier, and means to clamp the lifts in said recesses while the bases are out of contact with said wheel.

36. In a heel-lift assembling machine, a pair of rotatably mounted disks suitably spaced apart, a rotatable support at one side thereof, an endless carrier extending about and supported on the peripheries of said disks and said support and comprising a series of flexibly connected heel form bases having outwardly opening lift-receiving recesses, a lift-clamping plate for each recess outwardly and inwardly movable therein, a U-shaped operating device extending through each base and connected to the corresponding clamping plates, means to drive said disks and carrier in unison, and a series of regularly spaced abutments arranged between and connected to said disks, each operating device being arranged to pass between said disks and be engaged by one of said abutments as the corresponding form base passes into engagement with said disks, to press the plate thereof outwardly.

37. In a heel-lift assembling machine, a series of connected base plates, a correspond-

ing series of form plates, each having a lift-receiving recess on its upper side, and means for removably securing said form plates interchangeably on said base-plates in predetermined relative positions, substantially as described.

38. In a heel-lift assembling machine, a series of base-plates, each having a recess in its upper side, a series of form plates arranged to be interchangeably fitted in said recesses, each having an outwardly flaring, lift-receiving recess on its upper side, and means for removably securing each form plate in the recess of a base-plate, substantially as described.

39. In a heel-lift assembling machine, a series of heel holders flexibly connected to form an endless carrier, and having heel-lift receiving seats, means to drive said carrier to bring said holders successively to a lift-receiving position in which said seats face upwardly, forming means for guiding the lifts into heel form when placed on said seats, and a clamping device for each holder arranged to be held in a position at one side of its seat to permit the lifts to be assembled thereon and movable to a position thereover and then downwardly to clamp the lifts on the seat while held in position by said forming means.

40. In a heel-lift-assembling machine, an endless carrier composed of a series of flexibly connected heel holders each having an outwardly facing lift-receiving seat, a clamping plate for each holder and means to move each plate laterally over its seat and inwardly at one point in its travel of the carrier, to clamp the lifts thereagainst, and to move it outwardly and then laterally in the opposite direction at another point to permit them to be discharged.

41. In a heel-lift-assembling machine, an endless carrier composed of a series of flexibly connected heel holders, each having a lift-receiving seat, a clamping device for each holder movable to and from the seat thereof to clamp and release the lifts assembled thereon, means to drive said carrier in one direction to bring said holders successively into predetermined lift-receiving and heel-discharging positions, means normally actuated to move each clamping device into clamping position, and engaging devices disposed to move each clamping device away from its seat as its corresponding holder is moved into discharging position and to hold it out of clamping position while its holder is in receiving position.

42. In a heel-lift assembling machine, a support, an endless carrier, composed of a series of flexibly connected heel-holders each having a lift-receiving seat on its outer side, a clamping device for each holder movable to and from the seat thereof to clamp and release the lifts thereon, means to drive said

carrier in one direction about said support in a vertically disposed position, to move said holders vertically and horizontally successively, and means to move each clamping device outwardly to release a heel clamped thereby, when the holder thereof is in position to move upwardly and to move it to clamp the lifts on its corresponding seat when the holder is in a position to move

10 horizontally.

43. In a heel-lift assembling machine, an endless carrier composed of a series of flexibly connected heel holders having outwardly facing lift-receiving seats, means to drive said carrier in a path disposed in vertical planes, said path having horizontal upper and lower portions and downwardly and upwardly extending end-portions,

clamping devices for each holder movable toward and from the respective seats thereof, to clamp the lifts thereagainst and to release them therefrom, means to move each clamping device away from its corresponding seat as the holder thereof moves upwardly to a closely adjacent horizontal position, and means to move it toward its seat when its holder reaches said horizontal position.

In testimony whereof, I have signed my name to this specification, in the presence of two subscribing witnesses.

ERVIN L. PAGE.
